Primary Examiner — Mark A Goodwin
Assistant Examiner — Adam C Mager

(57) **CLAIM**

The ornamental design for an electric motorcycle as shown and described.

DESCRIPTION

The patent or application file contains at least one drawing executed in color. Copies of this patent or patent application publication with color drawing(s) will be provided by the Office upon request and payment of the necessary fee.

1. Electric Motorcycle

1.1: Perspective

1.2: Left

1.3: Right

1.4: Top

1.5: Bottom

1.6: Front

1.7: Rear

1 Claim, 7 Drawing Sheets
